(57) **CLAIM**

The ornamental design for a bedstead, as shown and described.

DESCRIPTION

FIG. 1 is a left front perspective view of a bedstead showing my new design;

FIG. 2 is a side elevational view, the opposite side being a mirror image thereof;

FIG. 3 is a front perspective view thereof; and,

FIG. 4 is a rear perspective view of the footboard section thereof.

The views of the bedstead not shown form no part of the claimed design. The dashed lines represent environmental elements only and form no part of the claimed design.

1 Claim, 4 Drawing Sheets
